UNITED STATES PATENT OFFICE.

WILLIAM EDWARD F. GIBSON AND IDA MAY JAMES, OF PORT COQUITLAM, BRITISH COLUMBIA, CANADA.

AUTOMOBILE-SIGNAL.

1,340,537.

Specification of Letters Patent. Patented May 18, 1920.

Application filed May 17, 1919. Serial No. 297,955.

To all whom it may concern:

Be it known that we, WILLIAM EDWARD F. GIBSON and IDA MAY JAMES, citizens of the United States, residing at Port Coquitlam, 5 Province of British Columbia, Dominion of Canada, have invented a certain new and useful Improvement in Automobile-Signals, of which the following is a specification.

Our invention relates to improvements in 10 signals used on automobiles or other moving vehicles to indicate the direction planned by the driver to take, either straight, or to the left, as the case may be, so as to give warning to those ahead, or at intersections or 15 bends or turns in streets or highways, to avoid collision or danger, and the object of our invention is to provide a device for this purpose which may be readily attached to an automobile in front and rear in such 20 positions as to be readily observed from both front and back, and which device is magnetically controlled as to its operating mechanism so that it is at all times positive in action and operable with great convenience 25 and facility.

A further object is to provide a suitable means for preventing inadvertent movement of such signals and maintaining them in 30 normal position until their operation becomes necessary. A still further object is to provide for the convenient and efficient operation of audible signaling means, such 35 as a horn, from the controlling means of the visible signals.

We accomplish these objects by the devices illustrated in the accompanying drawings, wherein—

Figure 1 is a view in side elevation of the front signal;

Fig. 2 is a view in side elevation of the rear signal;

Fig. 3 is a view in side elevation of the signal mechanism;

Fig. 4 is an end view of the mechanism, 45 one magnet leg being removed;

Fig. 5 is a plan view of the wire terminal and contact arrangement;

Fig. 6 is a sectional view of the same;

Fig. 7 is a view in cross-section of the 50 switch handle taken on broken line A, B of Fig. 6;

Fig. 8 is a view showing the signals in position on an automobile; and

Figs. 9 and 10 are diagrams illustrating the signal circuit wiring of our invention. 55

Like reference numerals indicate like parts throughout the drawings.

In the embodiment of our invention there are two signals, one for the front of the vehicle and one for the rear, the front signal A in Figs. 1 and 8 being positioned on the front fender on the drive side and the rear signal B in Figs. 2 and 8 being positioned on the rear fender, as shown in Fig. 8. Each respective signal consists of a suitable mounted casing rotatable about its vertical axis, which may be of some fanciful form, such as having the outline of a bird, within which casing is arranged the operating mechanism and which is actuated from a suitable electrical source, such as a battery, as will be hereinafter more fully described. As the mechanism in both front and rear signals is similar it will be necessary to describe the front signal mechanism only. 75

The numeral 1 indicates the casing, which is formed bird-shaped, which casing is provided on its lower side with a tubular extension 2 the lower end of which bears on a base plate 3 provided for the securing of the signal to the fender, the extension 2 being provided with a projection 4 on its inside at its lower end adapted to cooperate with the stop member 5 on the base plate 3 so as to limit the travel of the casing as it is rotated in either direction. 85

Secured rigidly to the base plate 3 and centrally thereof is a vertical tubular shaft 6 the upper end of which extends into the interior of the casing 1 and is formed as an integral bevel pinion 7, between which shaft 6 and the wall of the tubular extension 2 are disposed ball bearings 8, as shown in Fig. 3, these being provided to insure the free rotation of the extension 2 and the casing 1 of which it forms a part. 95

The upper end of the extension 2 extends within the casing, being flared and provided with flanges 9 and 10 on each side of its center line, on which flanges are supported the legs 11 and 12 of a magnet 13 which magnet consists of the legs 11 and 12 and a "field" winding secured between them at their upper ends, this winding being hereinafter termed the field 14. 100

15 and 16 indicate bars secured to the mag-

net 13 on each side thereof by suitable screws 17 and spaced apart therefrom by suitable distance pieces 18, on and between which bars, and between the poles of the 5 magnet 13, is rotatably mounted an armature 19, consisting of two circular side plates 20 and 21 having an armature 22 supported and secured therebetween, the plate 21 being provided on its lower semi-circular edge 10 with an integral toothed sector 23 meshing with the pinion 7. Distance pieces 24 and 25 are secured between the side plates 20 and 21 and on the upper distance piece 24 is secured a stop member 26 adapted to engage 15 the beveled edges 27 and 28, respectively, of the magnet 13 as the armature is rotated in either direction and for the purpose of returning the armature to its normal central position from the signaling position springs 20 29 and 30 are provided, each of these springs being connected at their upper ends to lugs 11 and 12, respectively, and their lower ends are connected to the distance pieces 18 as shown in Figs. 3 and 4.

25 31 indicates an incandescent bulb supported in a suitable socket 32 mounted on the inside of one leg of the magnet 13 and disposed centrally as shown in Fig. 3.

In order to prevent inadvertent movement 30 of the signal in a strong wind or by vibration a small magnet 33 is secured to one side of the magnet 13 on the outside of the same by any suitable means such as a bracket 34, the upper pole of the magnet 33 being secured 35 to the outstanding arm 35 of the bracket 34, which arm is turned downwardly, as shown at 36 in Fig. 3, to the lower end of which downwardly turned part is hingedly connected an armature 37, this 40 armature being supported adjacent the lower pole 38 of the magnet 33 and normally clear of the same. The armature 37 is turned down to form a depending leg 39, the lower end of which extends through an 45 opening in the casing 1 and normally engages a notch 40 in a transverse bridge member 41 which straddles the base plate 3 and is secured thereto by the same screws or bolts which fasten the signal to the fender. 50 The space between the pole 38 and armature 37 is more than the depth of the notch 40, from which it will be apparent that when the magnet 33 is energized the armature 37 will be drawn upwardly to raise the lower 55 end of the leg 39 out of the notch 40, thus permitting rotation of the signal, but when the magnet 33 is deenergized on the return of the signal to its normal central position the leg 39 will drop and its end will reengage the notch 40 to prevent inadvertent rotation of the signal.

The signals are operated from a suitable battery indicated by the numeral 74 in Fig. 9 and are controlled by means of a manually

operated switch lever 42 mounted on a contact plate 43, which plate may be secured to the steering column 44 adjacent the steering wheel 45, as shown in Fig. 6, or it may be secured to one of the spokes of the wheel if desired.

70 The contacts for the signal operation are as shown in Figs. 5 and 9, in which the plate 43 is of non-conducting material such as hard rubber or the like. Embedded in the plate are two outer brass segments 47 and 48 separated, as shown at 49, while 50 and 51 indicate two inner segments one of which, 51, is further divided into three parts, the main part 51 and two smaller parts 52 and 53 adjacent each end, all the segments being 80 concentric with the bolt 54 on which the lever 42 is rotatably mounted.

85 The switch lever 42 is provided on its underside with spring pressed contact points 55 and 56 so that when moved out of center to the right, as shown in Fig. 5, the point 55 will bridge the gap between part 52 and segment 51, making contact therebetween and also with outer segment 48, while at the same time contact 56 will make contact between inner segment 50 and outer segment 47. 90 Also when the switch lever is moved to the left as shown in Fig. 5, the contact point 55 will make contact between inner segment 50 and outer segment 48 and contact 95 point 56 will bridge the gap between part 53 and segment 51, making contact therebetween and also with the outer segment 47. The travel of the lever 42 in either direction is limited by upstanding pins 57 and 58, as 100 shown in Fig. 5.

105 61, 62, 63, 64, 65 and 66 indicate the connections or terminals of the several circuit wires, for operating the device, to the respective segments; and for a better understanding of the wiring arrangement reference should be had now to the diagram shown in Fig. 9, in which 14 and 19 represent the fields and armatures of the front and rear signals, respectively, it being understood, that both signals operate simultaneously. 110 It will be seen that armatures 19 are disposed in a circuit of which 67 indicates the wire which is connected by branch wires 68 and 69 to the terminals 61 and 62 of the outer segments 47 and 48 respectively and also that the fields 14 are disposed in a circuit of which 70 indicates the wire, and circuit 70 being connected to terminals 63 and 64 of the parts 52 and 53 by branch wires 115 71 and 72 and also to one terminal 73 of a battery 74 by a wire 75, the terminal 73 being named for the purpose of illustration, the negative. From wire 75 a branch wire 76 is led to the terminal 65 of the inner segment 50 while inner segment 51 is connected to the positive terminal 77 of the battery by a wire 78 leading therefrom to terminal 66.

79 and 80 indicate the circuits for lighting the lamps 31 simultaneously with the operation of the signals. Assuming now that the signals are pointing straight ahead as shown in Fig. 8 and referring to Figs. 5 and 9 it will be seen that when the switch lever 42 is moved to the left, contact point 55 will make contact with segments 48 and 50 and also point 56 will make contact with segments 51, 53 and 47 and thus the current will flow from the positive terminal 77 of the battery 74 along wire 78, segment 51, part 53, across segment 47 to branch wire 68 to wire 67 of the armature circuit returning through wire 62 to segment 48, across to segment 50 through contact point 55, and back to the battery through wires 76 and 75 connected to the negative terminal 73. At the same time the current also flows from the positive terminal 77 of the battery through wire 78, segment 51, part 53 and wires 72 and 71 to the field circuit wire 70, returning to the negative terminal 73 of the battery through wire 75.

25 It will be apparent that when the switch is moved to the left the field 14 of each signal will be energized by a positive current, thus magnetizing the magnet 13 and creating its opposite legs north and south poles. At the same time the armatures 19 are energized by the positive current creating the distance pieces 24 and 25 north and south poles, respectively, from which it will readily be seen that the north and south 35 poles of the magnet will repel and attract the north and south poles of the distance pieces 24 and 25 causing it to rotate until the stop member 26 prevents further rotation, and as the sector 23 is in mesh with the fixed 40 pinion 7 the signal will thus be swung from its normal longitudinal straight ahead position to a transverse position, being returned to its normal position when the switch is moved to mid-position by means of the 45 spring then in tension. On moving the switch to the right the casing will be swung to the opposite transverse position because the current being now negative, the distance pieces 24 and 25 will now be south and north 50 poles instead of north and south poles as before, and the armature will be rotated in the opposite direction since the poles of the magnet remain the same.

Now, the front signal being provided with 55 openings 79 and 80 on each side in the shape of a forwardly pointing hand and the rear signal being provided on one side with a similar hand shaped opening and on the other side with an opening closed by a white 60 semi-transparent plate 81 having painted thereon the word "Stop," the other openings being closed by similar plates and each plate being covered on its inner side with a sheet of red transparent material, as indicated at

82 in Fig. 4, it will be seen that when the 65 signals are mounted on the front and rear of the vehicle they will indicate straight ahead when in the normal position, but they may be operated in the manner described to 70 swing the front signal so that the hand will point to the right or left, as the case may be, and the rear signal so that the hand will indicate the direction of the vehicle or show the word "Stop" to those approaching from the rear. Illumination of the hands and 75 the word "Stop" is effected at night by means of the lamps 31, the red material 82 causing them to appear red.

The rear signal is provided at its rear end with a red glass-covered opening 83 illuminated at night by a lamp 84 disposed in the lighting circuit of the vehicle to act as a tail light and on its bottom side with a glass-covered opening 85 also illuminated by the lamp 84 to throw light on the license tag. 85

In order to provide for the operation of the armatures 37 and their coöperating magnets 33 simultaneously with the operation of the signals the switch lever 42 is provided with a transverse contact bar 86 having its 90 ends turned downwardly and forming contact points 87 and 88 positioned normally clear of any contact on the plate 43 as shown in Fig. 10, but which, when the switch is moved either to the right or left, will make 95 contact with segments 89 and 90 or 91 and 92, as the case may be, these segments being placed in the plate 43 between the outer and inner segments 47 and 51 and 48 and 50, as shown in Fig. 5, and from which segments 100 wires 93 and 94, shown in Fig. 3, are led to the magnet 33, the segments being of course suitably connected to the battery 74.

The signaling horn of the vehicle is operated from the switch also and its operation 105 is provided for by the mounting on the plate 43 of a contact segment 95 and connecting this segment and also the bolt 54 to the battery and horn circuit by suitable wires, indicated at 96 and 97 in Fig. 6, the 110 circuit being closed to sound the horn 105 by the manual depression of a button contact 98 resiliently secured to the switch lever, the release of the contact 98 permitting it to spring up to its normal position clear 115 of the segment 95 and thus break the horn circuit. The button contact 98 also acts as a handle for operating the switch lever 42, as the depression plate 99 which carries the contact has its sides turned down so as to 120 engage the sides of the lever 42, as shown in Figs. 6 and 7, and enable it to be moved in the required direction.

From the foregoing it will be seen that we have devised a vehicle signal which is at all 125 times positive in action and operated with great convenience and facility. As many changes could be made in the construction

described in the foregoing description within the scope of the following claim without departing from the spirit thereof.

What we claim is:

- 5 In a device of the class described, a casing provided on either side with an indicator, a pinion within said casing having its hub extended as a tubular shaft adapted to be secured to the vehicle body and forming a
- 10 rigid vertical axis on which said casing is rotatably mounted, a magnet mounted within and secured to said casing; an armature within the casing rotatably mounted between the poles of the magnet and provided with
- 15 a toothed sector meshing with said pinion, a

normally deenergized magnet mounted on the first mentioned one, a hinged vertically movable armature disposed adjacent a pole of the last mentioned magnet and having its free end turned downwardly and extending 20 through the casing, a member having a socket in which the free end of the vertically movable armature is normally engaged, and means for temporarily magnetizing the first mentioned armature and simultaneously energizing the last mentioned magnet.

In witness whereof we hereunto subscribe our names this 10th day of May, A. D. 1919.

WILLIAM EDWARD F. GIBSON.
IDA MAY JAMES.
